DESIGN FOR A CONTAINER MOUNTING BRACKET

William B. Johnson, United States Army

Application October 22, 1941, Serial No. 103,863

Term of patent 3½ years

To all whom it may concern:

Be it known that I, William B. Johnson, whose residence is United States Army, a citizen of the United States, have invented a new, original, and ornamental Design for a Container Mounting Bracket, of which the following is a specification, reference being had to the accompanying drawing, forming part thereof.

Fig. 1 is a top plan view of a container mounting bracket, showing my new design.

Fig. 2 is a front elevational view.

Fig. 3 is an end elevational view.

Fig. 4 is a fragmentary rear elevational view.

I claim:

The ornamental design for a container mounting bracket, as shown.

WILLIAM B. JOHNSON.
